UNITED STATES PATENT OFFICE.

CHARLES PETERSON, OF LEAL, NORTH DAKOTA.

FIRE-ALARM.

1,322,336.

Specification of Letters Patent. Patented Nov. 18, 1919.

Application filed December 17, 1914. Serial No. 877,739.

To all whom it may concern:

Be it known that I, CHARLES PETERSON, a citizen of the United States, residing at Leal, in the county of Barnes and State of North Dakota, have invented certain new and useful Improvements in Fire-Alarms; and I do hereby declare the following to be a full, clear, and exact description of the invention, such as will enable others skilled in the art to which it appertains to make and use the same.

My invention relates to improvements in fire alarms of the electrically operated type and resides in the provision of an alarm which comprises audible signaling means that is electrically operated and has its electrical circuit normally open and provided with novel circuit closing means arranged to close the circuit when fire breaks out at a given point.

Another object is to provide a fire alarm for dwellings, such as stores, hotels, private dwellings and also ships which is arranged so that various parts of the dwelling or ship may be protected against fire so that should a fire break out the alarm will immediately operate thus preventing the fire gaining headway.

Another and more specific object is to provide a fire alarm which comprises an audible signal which may be arranged at any suitable point within a dwelling, for example, in a bed room, an electrical circuit being provided for the audible signal and automatic circuit closing means associated with the circuit, the automatic circuit closing means consisting of spaced contact members, and a weight normally suspended above the spaced contact members by means of an inflammable cord or like element, which cord is arranged about the room of a dwelling in any suitable manner and preferably at points where a fire is apt to start in order that the weight will be released, when the cord catches fire and parts, to effect a closing of the circuit for the signal.

Another object of my invention is to provide simple and effective means of the above mentioned character that may be easily and cheaply installed, is reliable and efficient in operation and which may be so positioned relative to a building as to not take up much room.

The above and additional objects are accomplished by such means as are illustrated in the accompanying drawings, described in

the following specification and then more particularly pointed out in the claim.

With reference to the drawings, wherein I have illustrated the preferred embodiment of my invention as it is reduced to practice, and throughout the several views of which similar reference numerals designate corresponding parts,

Figure 1 is a sectional view taken through a building showing my improved signal as it would appear when in use and the signaling means in side elevation,

Fig. 2 is a fragmentary front elevation of a part of dwelling showing the signaling means in front elevation,

Fig. 3 is an enlarged front elevation of the circuit closing means and battery casing, and

Fig. 4 is a diagrammatic view of the signal.

Referring to the drawings by characters of reference A represents a section of a dwelling or ship which comprises side walls 1 and ceilings 2.

In carrying out my invention, an audible signal 3, preferably an electric bell is placed within one of the rooms, preferably the bed room of the dwelling A and electrically connected by means of conductors 4 and 5 with a dry cell 6 or other suitable source of current that is placed within a rectangular casing 7, the casing 7 being provided with attaching ears 8 at its ends and being secured upon the wall of a room in another part of the dwelling, preferably in some part of the dwelling adjacent to which is stored combustible material.

The casing 7 is divided into two compartments, B and C respectively by means of a longitudinal partition 9. The battery 6 is contained within the compartment B. Carried within the lower end of the compartment C are spring, normally spaced contact members 10 and 11, the one 11 being disposed above the one 10 and arranged to be forced into contact therewith. The conductor 4 is connected with the contact 11 and a conductor 12 leads from the contact 10 to the battery 6.

Carried within the compartment C is a weight member 13 that is normally held in spaced and suspended relation to the contacts 10 and 11 by means of an inflammable cable or cord 14 which is secured to an eye 15 carried on the upper end of the weight. An aperture 16 is formed in the upper end

wall of the compartment C and slidably receives the cord or cable 14. The casing is also provided with a narrow, oblong horizontally disposed bottom compartment or space 5 to receive the wires, which extend from the contacts into the battery receiving compartment.

The casing 7 is preferably secured in a vertical position upon the side wall of a room at a point below the ceiling 2, and the cable 14 is directed upwardly and engages and passes over a pulley 17 that is carried by the ceiling 2. The cable is extended across the room at the ceiling 2 and passed 10 over a pulley 18 similar to the one 17 at the opposite side of the room and allowed to hang from the pulley in alignment with the opposite side wall. At the other end of the cable is carried a balance weight 19 which 15 is heavier than the weight 13 and normally holds said weight 13 in suspended relation to the contacts 10 and 11. This cable 14 may be placed zig zag across the ceiling of the room or arranged in any other suitable 20 manner, not shown, relative to the walls and ceiling of the room, in any way, which will allow for the supporting of the weight 13 in spaced relation to the normally spaced contacts 10 and 11.

30 In operation, should a fire break out within the room in which the cable 14 is arranged, the cable catches on fire and parts allowing the weight 13 to drop into engagement with the contact 11 and force said contact into engagement with the contact 10. The weight 13 is sufficiently heavy to hold the contacts in contacting relation thus the circuit for the audible signal 3 is kept closed and the signal operated until the weight 13 35 is removed from engagement with the contacts. The cord or cable 14 is preferably waxed or oiled so that it will catch afire readily.

The casing 7 is provided with a hinged 45 door 20 so that access to the mechanism therein may be had. The casing may be constructed of fire-proof material.

With reference to the foregoing description and accompanying drawings it will be 50 observed that I have provided a fire alarm which will operate automatically to indicate the presence of fire in various parts of a dwelling or like structure and which will

prove of great service to farmers in that it may be connected with the barn in such manner that the owner will be alarmed in case of fire in the barn.

In practice, I have found that the form of my invention, illustrated in the drawings and referred to in the above description, as 55 the preferred embodiment, is the most efficient and practical; yet realizing that the conditions concurrent with the adoption of my device will necessarily vary, I desire to emphasize the fact that various minor 60 changes in details of construction, proportion and arrangement of parts may be resorted to, when required, without sacrificing any of the advantages of my invention, 65 as claimed.

70 What is claimed is:—

A fire alarm of the character set forth including a casing open at its front side and having a pair of vertical compartments and a horizontal compartment located immediately below the vertical compartments, a 75 battery located within one of said vertical compartments, spaced resilient contacts located within the other vertical compartment and secured to the bottom wall thereof, a wire connected to one pole of the battery and extending through the top wall of the casing, a second wire connected to the other pole of the battery and to one of said contacts, said second wire being housed in the 80 battery receiving compartment and in said horizontal compartment and extending through the bottom wall of each vertical compartment, a third wire passing through the top wall of the casing into the battery receiving compartment and through the bottom wall of said compartment into the horizontal compartment and thence through the bottom wall of the other vertical compartment and attached to the other of said contacts, a weight suspended within said other vertical compartment above said contacts and having a width less than the width of the compartment, and a removable closure 85 for the open side of the casing.

90 In testimony whereof I affix my signature in presence of two witnesses.

95 CHARLES PETERSON.
